MICROBIOLOGICALLY ACTIVE QUATERNARY AMMONIUM COMPOUNDS

Reginald L. Wakeman, Philadelphia, Pa., and Joseph F. Coates, Washington, D.C., assignors, by mesne assignments, to Millmaster Onyx Corporation, New York, N.Y., a corporation of New York
No Drawing. Filed Apr. 3, 1964, Ser. No. 357,263
8 Claims. (Cl. 260—501.15)

The present invention has for its object the preparation of relatively water-insoluble, microbiologically active compounds by reaction of certain quaternary ammonium hydroxides or their water-soluble salts with alkyl-substituted aromatic carboxylic acids or their water-soluble salts.

The quaternary ammonium compounds used in the process of this invention are all bacteriologically active, having a phenol coefficient of at least 100 with respect to both *Staphylococcus aureus* and *Salmonella typhosa* at 20° C., when determined by the standard method given in the United States Department of Agriculture Circular No. 198. They contain at least one carbon chain having from 8 to 22 carbon atoms and also possess at least one benzyl radical attached to the quaternary nitrogen atom. The benzyl radical may, if desired, be substituted by alkyl groups or halogen atoms. The quaternary ammonium compounds, moreover, possess only non-heterocyclic nitrogen atoms. In general, the quaternary ammonium compounds used in the present invention comply with the formula:

where R' is an alkyl radical containing from 8 to 22 carbon atoms, an alkyl benzyl radical in which the benzyl group may contain a substituent methyl radical and in which the alkyl group contains 8 to 22 carbon atoms, or an alkyl phenoxy ethoxy ethyl radical in which the phenyl group may contain a substituent methyl radical and R'' is a benzyl or substituted benzyl radical, or a methyl group if R' is an alkyl benzyl radical containing eight or more carbon atoms in its alkyl substituent. X in the above formula is chlorine, bromine, iodine, sulfate, methosulfate, ethosulfate and the like.

Typical examples of these quaternary ammonium compounds are alkyl dimethyl benzyl ammonium chloride in which the alkyl group may have from 8 to 22 carbon atoms, alkyl dimethyl substituted benzyl ammonium chlorides, in which the alkyl radical contains from 8 to 22 carbon atoms and in which the benzyl radical is substituted with one or more side chains containing from 1 to 5 carbon atoms such, for example, as methyl, dimethyl, trimethyl, tetramethyl, ethyl, diethyl, isopropyl, tertiary butyl and isoamyl or with one, two, or more, halogen atoms such as chlorine or bromine, alkyl dimethyl methaphyl ammonium chloride and alkyl dimethyl tetrahydromenaphyl ammonium chloride in which the alkyl radical contains from 8 to 22 carbon atoms, alkyl benzyl trimethyl ammonium chloride in which the alkyl radical contains from 8 to 22 carbon atoms and in which the aromatic nucleus of the benzyl radical may, if desired, be substituted by one or more methyl or other lower alkyl groups, alkyl phenoxy ethoxy ethyl dimethyl benzyl ammonium chloride in which the alkyl radical may be iso-octyl or nonyl, and mixtures of the aforesaid quaternary ammonium compounds.

The alkyl-aromatic monocarboxylic acids which are

2

used in the present invention correspond to the general formula

hibit high microbiological activity despite their relative in- where R is a mono- or poly- alkyl substituted benzene or naphthalene nucleus, or the substituted nucleus of diphenyl or diphenyl oxide in each of which cases the substituents may be radicals having from 1 to 22 carbon atoms, and Z is

where n is any number from zero to four.

Typical examples of the alkyl-aryl carboxylic acids which may be used in the practice of this invention in- clude o-, m- and p- tolueic acids, the various isomers of dimethyl benzoic acid and trimethyl benzoic acid, o-, m- and p- ethyl or isopropyl benzoic acid, hexyl, octyl, or decyl benzoic acid and the like, methyl- or ethyl- cinnamic acid or hydrocinnamic acid, the various isomers of methyl- naphthoic acid the like.

The compounds of this invention may be prepared by mixing an aqueous solution of the quaternary ammonium salt or hydroxide of the kind defined above with an aqueous solution of the acid in question or with any of its water-soluble salts.

After thorough mixing, the organic product layer is sep- arated from the aqueous layer (as with a separatory funnel) since two distinct phases are formed. Separation may be facilitated by the addition of an organic solvent im- miscible with water. The product layer may be washed with water to remove any residual by-product salt or un- reacted materials. The solvent, if any, may be evaporated and the product air or vacuum dried to a paste, wax, oil or solid.

It is not necessary to use an aqueous medium. Any sol- vent or solvent mixture in which the starting materials are soluble will be satisfactory. Non-acqueous solvents facil- itate the separation of by-product inorganic salt and re- duce the need for vacuum drying to get an anhydrous product. When a non-aqueous medium is employed, it is usually necessary to add a small amount of water to facil- itate ionic reaction.

The product may be used, if desired, without drying since any entrapped water is irrelevant to the microbio- logical activity of the compounds. In other applications, removal of water may be essential for reasons not related to biological activity.

An alternative method for the preparation of com- pounds especially applicable to the treatment of fabric, 50 ropes, net, woven and non-woven fabric and reticulated or convoluted materials, involves a two-step process. In the first step, the material is passed through a bath containing the anionic moiety. Excess solution is removed by methods well known to those skilled in the art. The 55 treated material is then passed through a second bath wherein the concentration of quaternary ammonium com- pound is such that the material pickup will result in an equivalent amount of quaternary ammonium compound reacting with the anionic moiety, depositing the product in the most intimate way on the surface and in the inter- stices, convolutions and reticulations of the material.

The method of adjustment of solution concentration to achieve the required pickup is well known to those skilled in the art. The order of treatment may be reversed with- 65 out affecting the biological activity or durability of the product on the material. The products of this invention may be formulated as water dispersions by dissolving them in a water-miscible organic solvent such as acetone or methanol and diluting with water or by dissolving them in emulsifiable oils such, for example, as sulfonated castor oil or pine oil and diluting with water. In preparing aqueous dispersions, emulsifying agents such, for example,

as ethylene oxide condensates of alkyl phenols may be used with or without organic solvents.

It is surprising that the compounds of this invention ex-solubility in water. Because of their unusual combination of physical and microbiological properties, they can be used to impart laundry-resistant anti-microbial characteristics to textiles. They can also be used as the active agent in antimildew finishes for textiles which are resistant to leaching with water.

Although the compounds have low water solubility, they are compatible with various organic solvents, plasticizers and high molecular weight compounds. Consequently, they may be incorporated as anti-microbial agents in synthetic resins and plastics. The compounds are compatible with natural and synthetic rubber latices. Therefore, they may be used to prepare bacteriostatic films and molded objects deposited from such latices.

The compounds can be incorporated into cutting and grinding fluids without precipitation. Also, they blend well with non-ionic and anionic surface active agents. In such compositions they retain their microbiological activity.

It will be understood that the properties of the products described herein will vary depending upon the nature of the quaternary ammonium compound used in their preparation as well as the aromatic carboxylic acid or salt reacted therewith.

The chemical, physical and biological properties of the products of our invention make them especially appropriate for the following applications when suitably incorporated in active amounts in an appropriate vehicle, binder, medium or substrate:

- (1) Mildewproofing fabric, canvas, ropes, textiles, awnings, sails, tenting and other woven and non-woven reticulated materials.
- (2) Paint mildewstats.
- (3) Jet plane fuel additive to control growth of micro-organisms.
- (4) Odor preservative agents for clothes and shoes.
- (5) Mildew retardant and odor suppressant for shoes and other leather products.
- (6) Topical antiseptics.
- (7) Antidandruff agents.
- (8) Disinfection agents for hair and gut of man and beast.
- (9) Bacteriostatic furniture dressing.
- (10) Surface finishes for stone, plaster, tile, cement, brick and other inorganic building materials, to retard growth of microorganisms, fungi, mold and algae.
- (11) Wool preservative.
- (12) Plant and tree spray to combat fungi.
- (13) Antimycotic agents for soap wrappers.
- (14) Self-sanitizing brushes.
- (15) Mildewproofing agent in and on plastic and film.
- (16) Mildewproofing of cellulosics, cardboard, fibreboard, paper and cordage.
- (17) Contact biostat for application to film, waxes and cloth to preserve cheese, meats and vegetables and other food products.
- (18) Algal inhibition, especially on surfaces and in solution where low foaming is desirable.
- (19) Paper pulp slime control.
- (20) Sanitizing agent for rug, carpet, curtains.
- (21) Egg preservation.
- (22) Adhesive preservation.
- (23) Preservation of latex paints.
- (24) Preservation of metal-working compounds.
- (25) Additives for soap and for both anionic and non-ionic detergents in liquid, bar, powder, bead, solution and other forms to impart bacteriostatic and fungistatic properties thereto.

The microbiological activity of our compounds has been evaluated for microbiological stasis by the Standard Tube Dilution Test, the technique for which is common knowledge to those skilled in the art. A Difco Bacto

CSMA Broth #0826 was used in the study. This test is used to determine the lowest concentration of microbiologically active compounds which will inhibit the growth of the organism in question. For a wide range of applications, the inhibition of growth rather than outright kill is satisfactory.

Briefly put, the Tube Dilution Test consists in placing 9 cc. of the CSMA Broth in a test tube which is then sterilized in an autoclave. One cc. solution of the microbiologically active compound at an appropriate concentration is added to the test tube which is then inoculated with 0.1 cc. of a twenty-four hour old culture of the organism under study. The test tube is then incubated at 37° C. for forty-eight hours and observed for bacterial growth.

The same procedure is followed for fungi. In such tests, however, the tubes are incubated for fourteen days at a temperature suitable for optimum fungal growth, usually 25° C.

The invention is illustrated by, but not restricted to, the following examples:

Example I

25 A stock solution was prepared containing 5% by weight of the sodium salt of p-toluic acid. To a vigorously agitated aliquot of this solution containing 0.041 equivalent weight of the compound was added the chemically equivalent amount of an 11% solution of a commercial grade of alkyl dimethyl ethyl-benzyl ammonium chloride (Onyx Chemical Corporation, "BTC-471," in which the alkyl distribution is 50% C₁₂, 30% C₁₄, 17% C₁₆, 3% C₁₈). The agitated mixture was poured into a separatory funnel and separated into two phases. The organic product layer was removed and vacuum dried to a yellow paste, in 100% theoretical yield, of alkyl dimethyl ethyl-benzyl ammonium p-toluate.

Similar products were prepared by replacing the p-toluic acid with m-toluic acid and o-toluic acid.

Example II

The solution of sodium p-toluate of Example I was treated in the same manner and in the same amount with a chemically equivalent amount of a solution of a commercial grade of alkyl dimethyl benzyl ammonium chloride (Onyx Chemical Corporation, "BTC-824," in which the alkyl distribution is 60% C₁₄, 30% C₁₆, 5% C₁₂, 5% C₁₈). The agitated mixture was transferred to a separatory funnel and separated into two phases. The separated organic compound layer on vacuum drying yielded a white paste, in theoretical yield, of alkyl dimethyl benzyl ammonium p-toluate.

Similarly, by substituting m-toluic acid for p-toluic acid, the alkyl dimethyl benzyl ammonium m-toluate was obtained in theoretical yield.

Example III

30 A stock solution was prepared containing 5% by weight of the sodium salt of octyl-benzoic acid. An aliquot containing 0.064 equivalent weight of the compound was agitated vigorously, while adding the chemically equivalent amount of an 11% solution of the alkyl dimethyl benzyl ammonium chloride of Example II. The agitated mixture was separated in a separatory funnel. The organic product layer was vacuum dried to a yellow paste, in theoretical yield, of alkyl dimethyl benzyl ammonium octyl-benzoate.

Example IV

75 The products of Example I and II were tested by the Standard Tube Dilution Test described above against *Staphylococcus aureus* (*S.a.*), *Salmonella typhosa* (*S.t.*) and *Aspergillus niger* (*A.n.*). Results are shown in Table I.

TABLE I

Quaternary	Acid	Reciprocal of Static Dilution of Product vs.—		
		S.a.	S.t.	A.n.

Alkyl Dimethyl Benzyl Ammonium Chloride.	p-Toluic	10 ⁶	10 ⁵	10 ⁶
	m-Toluic	10 ⁶	10 ⁵	10 ⁵

We claim:

1. A compound having the structure:

wherein R' is a member of the group consisting of alkyl, alkyl benzyl, alkyl methyl-benzyl, alkyl phenoxy ethoxy ethyl and alkyl phenoxy ethoxy ethyl having a methyl substituent on the phenyl group, the alkyl in each case having 8 to 22 carbon atoms, R'' is a member of the group consisting of benzyl, lower alkyl-substituted benzyl and methyl, R'' being methyl when R' is alkyl benzyl, R is a member of the group consisting of alkyl substituted benzene, alkyl substituted naphthalene, alkyl substituted diphenyl and alkyl substituted diphenyl oxide, said alkyl having 1 to 22 carbon atoms, and Z is a member of the group consisting of (CH₂)_n and (CH₂)_n—2H wherein n is a number from 0 to 4.

2. The compound as defined in claim 1, wherein the carboxylic acid is selected from the group consisting of o-, m-, and p-tolanic acids, dimethyl benzoic acid, trimethyl benzoic acid and its isomers, o-, m- and p-ethyl benzoic acids, o-, m- and p-isopropyl benzoic acid, o-, m- and p-hexyl benzoic acid, o-, m- and p-octyl benzoic acid, o-, m- and p-decyl benzoic acid, o-, m- and p-methyl-

and ethyl-cinnamic and hydrocinnamic acids, and methyl naphthoic acids, and its isomers.

- 15 3. Alkyl dimethyl ethyl-benzyl ammonium p-toluate wherein the alkyl has 12 to 18 carbon atoms.
4. Alkyl dimethyl ethyl-benzyl ammonium p-toluate wherein the alkyl has 12 to 18 carbon atoms.
5. Alkyl dimethyl ethyl-benzyl ammonium o-toluate wherein the alkyl has 12 to 18 carbon atoms.
- 20 6. Alkyl dimethyl benzyl ammonium p-toluate wherein the alkyl has 12 to 18 carbon atoms.
7. Alkyl dimethyl benzyl ammonium m-toluate wherein the alkyl has 12 to 18 carbon atoms.
- 25 8. Alkyl dimethyl benzyl ammonium octyl-benzoate wherein the alkyl has 12 to 18 carbon atoms.
